DA-582

EX

OF D 16.183

A. PETZOLD.

RUG.

No 16,183.

Patented July 28, 1885.

UNITED STATES PATENT OFFICE.

ADOLPH PETZOLD, OF PHILADELPHIA, PENNSYLVANIA.

DESIGN FOR A RUG.

SPECIFICATION forming part of Design No. 16,183, dated July 28, 1885.

Application filed April 11, 1885. Term of patent 3½ years.

To all whom it may concern:

Be it known that I, ADOLPH PETZOLD, a citizen of the United States, and a resident of Philadelphia, Pennsylvania, have invented and produced a new and original Design for a Rug, of which the following is a specification, reference being had to the accompanying photographic illustration, to which reference is made.

10 The accompanying photographic illustration shows all of my design with the exception of one end panel, which is omitted, as it is a duplicate of the end panel shown.

15 My design consists of an outer border, A, a middle panel, B, the latter ornamented as follows, viz: A large central figure, C, represents a flower resembling a dahlia, with sprays D of vines or branches in various directions. Leaves E, shaped like oak-leaves, rose-leaves

20 F, cherry-leaves G, and other shaped leaves H I J fill up the spaces between the flowers; K K, figures resembling acorns attached to sprays D D; a star-shaped flower, L, with a round center; a star-shaped flower, M, with

25 much more blunt points than flower L, and a flower, N, resembling a passion-flower. At each end of this middle panel is an end panel, O, in three arches, P Q R. Between the two end arches and the middle arch, at the hang-

30 ing points of junction of the arches, are rosettes S S, with pendants T T. Beneath the center of the middle arch is a trefoil figure, U,

composed of two side sprays of fanciful leaves and a central flower. (See illustration.) Beneath this figure and connected with it are 35 two side ornaments consisting of two sprays, V V, of leaves, the main stems having the same curves as "Hogarth's line of beauty." Beneath the point of junction of these two sprays is a large star-shaped flower, V'. Between the long edges of the middle panel, B, above and below, and the outer border, A, are broad interior strips, W W, each ornamented with U-shaped figures, the ends of the upright bars of which bend outward. (See illustration.) Small urn-shaped figures X are set 45 between these U-shaped figures.

The leading features of my design are the outer border, A, inner middle panel, B, ornamented with the central flower, C, and the 50 flowers I, M, and N, with sprays and leaves, substantially as shown, side strips, W W, and end panels, O, provided with arches P Q R, rosettes S S, trefoil figure U, and the leaved sprays V V, curved as shown, and large star-shaped flower V'.

What I claim as new is—

The design for a rug, substantially as shown and described.

ADOLPH PETZOLD.
